UNITED STATES PATENT OFFICE.

JOHN PERNAT, OF CLEVELAND, OHIO.

AUTOMATIC RAILWAY-GATE.

No. 882,342.

Specification of Letters Patent. Patented March 17, 1908.

Application filed December 17, 1907. Serial No. 406,853.

To all whom it may concern:

Be it known that I, JOHN PERNAT, citizen of United States, residing at Cleveland, in the county of Cuyahoga and State of Ohio, 5 have invented certain new and useful Improvements in Automatic Railway-Gates, of which the following is a specification.

My invention relates to improvements in automatic safety gates for railway crossings. 10 The primary object of the invention is to provide a railway crossing gate mechanism which will be simple and practical in construction, durable in use, comparatively inexpensive to produce and reliable and automatic in operation.

Another object of the invention is to provide a gate mechanism of this character in which a plurality of double crossing gates will be simultaneously actuated by a single 20 weight operated mechanism, the latter being automatically controlled by passing trains.

A further object of the invention is to provide an improved alarm bell mechanism which will be operated by the gates.

With the above and other objects in view the invention consists of the combinations and arrangements of parts and the novel features of construction hereinafter fully described and claimed, and illustrated in the 30 accompanying drawings in which:

Figure 1 is a plan view of my improved automatic railway gate; Fig. 2 is a side elevation of the same; Fig. 3 is an enlarged side elevation of the weight operated mechanism; 35 Fig. 4 is a top plan view of the same; Fig. 5 is an elevation of the opposite side of the mechanism shown in Fig. 3; and Fig. 6 is a detail view of one of the double gates operated by the weight mechanism.

In the drawings 1 denotes a double railway track and 2, 3, 4, 5, denote four double railway crossing gates of the usual form, each gate having a long gate arm 6 to extend half-way across a street, road or other highway 45 and a short gate arm 7 to project over the sidewalk. These gates are arranged in the usual manner, that is, in pairs one pair being on each side of the road and the gates of each pair being disposed on opposite sides of the 50 track in transverse alinement.

In the gates 3, 4, 5, the arms 6 are pivoted at 8 upon the enlarged upper ends of standards 9 or other suitable supports and the arms 7 are similarly pivoted at 10 upon said

standards, said pivots 10 having their ends 55 supported by brackets 11 as more clearly shown in Fig. 6. The arms 6, 7, are each preferably constructed of united longitudinal members or bars the inner ends of which are spaced apart to receive the standard 9 between them. Pivoted links 12 connect said arms 6, 7 so that they will swing simultaneously in opposite directions and their downward movement is preferably limited by stop pins 13 arranged upon the arms 6 and adapted 60 to engage the brackets 11, as seen in Fig. 6.

In the gate 2 the arms 6, 7 are similarly constructed and mounted on pivots 14, 15 arranged in a standard or support 16 of irregular form as shown in Figs. 3, 5. Said 70 arms of this gate are connected together for simultaneous movement by a link 17 and one of the members of the arm 6 is extended beyond the pivot 14 and provided with a weight 18 which serves to counter-balance 75 the arms.

The weight operated mechanism which serves to simultaneously raise or lower the arms 6, 7 of the four gates 2, 3, 4, 5, is preferably mounted upon the support or standard 80 16 and comprises an oscillatory element or member 19 in the form of a circular plate or disk pivoted at its center upon a pivot 20 projecting from one side of the support 16. Said disk or element 19 is adapted 85 to have a limited rotary or oscillatory movement and is operatively connected to the gate arms by a sprocket chain 21 passed over a sprocket wheel 22 fixed to the pivot 14 which carries the gate arm 6, as shown in 90 Fig. 3. The ends of the chain are connected to the periphery of the disk at points about 90° apart.

The disk or element 19 is adapted to be actuated in opposite directions by two 95 weighted levers 23, 24 which are in turn actuated by trip devices arranged along the track in the path of operating devices upon the passing trains. Said levers have their inner ends fulcrumed upon the pivot 20 and 100 are provided at their outer or free ends with suitable weights 25. Each lever carries a dog or pawl 26 which is pivoted at its upper end at 27 upon the lever and is formed intermediate its ends with a tooth 28 adapted to 105 engage one of two series of ratchet teeth 29, 29' formed at suitable points upon the disk or element 19. Said pawls are actuated by

springs 30 which tend to move the teeth 28 toward the ratchets 29. The lower ends 31 of the pawls are curved or cam-shaped to coact with a trip pin or projection 32 which 5 is arranged upon the support 16 and adapted to spread the pawls apart to disengage the teeth 28 from the ratchets 29 when the levers reach their lowered position shown in Fig. 3.

The lever 23 as it swings downwardly is 10 adapted to actuate the disk or element 19 in a direction that will cause the gate arms 6, 7 to be elevated, and it is lifted to its elevated position shown in dotted lines in Fig. 3 by the movement of trip levers 33, 34 of any 15 suitable form and construction arranged along the track 1 and adapted to be actuated by suitable devices upon passing cars or trains. Said trip levers 33, 34 are connected to the ends of cables 35, 36 which pass around 20 suitable guide pulleys 37 and have their opposite ends connected to a chain 38 which passes around a guide pulley 39 on the support 16 and is connected to one end of a sprocket chain 40. The latter, as seen in 25 Fig. 5, passes over a guide sprocket wheel 41 on the support 16 and is adjustably connected to the lever 23.

The lever 24 as it swings downwardly actuates the disk 19 in the reverse direction to 30 lower the gate arms 6, 7; and said lever 24 is lifted by trip levers 42, 43 which are similar to the levers 33, 34. The levers 42, 43 are connected to cables 44, 45 which are passed over guide pulleys 46 and are connected to one end of a chain 47. The latter passes around a guide pulley 48 and is connected to a sprocket chain 49 which in turn passes around a guide sprocket wheel 50 and is adjustably connected to the lever 24.

40 Each of the gates 3, 4, 5, is actuated from the gate 2 and has upon its arm 7 a sprocket wheel 55 over which passes a sprocket chain 54', as clearly shown in Fig. 6 which is a view of the inner side of the gate 4. For the 45 purpose of actuating the gate arms of the gates 3, 4 from the gate 2, I provide upon the pivot 14 a sprocket wheel 51 (as shown in Figs. 3, 4) over which passes a sprocket chain 52 having one of its ends connected to 50 a cable 53. The latter, as seen in Fig. 1, passes over guide pulleys 54 and is connected to one end of the chain 54' of the gate 3. The other end of the chain 54' of gate 3 is connected to a cable 53^a which extends 55 across the tracks, as shown in Fig. 1 (and over suitable guide pulleys not illustrated) and is connected to one end of the chain 54' of the gate 4 as seen in Fig. 6. The other end of chain 54' of gate 4 is connected to a 60 cable 53^b which passes over guide pulleys 54^a (see Fig. 1) and is connected to the other end of the chain 52, as shown in Fig. 3.

The arms of the gate 5 are similarly operated from the gate 2 by providing upon the 65 pivot 14 a third sprocket wheel 56 for a

sprocket chain 57 which is connected to a cable 58. The latter, as shown in Fig. 1, extends across the track and has included in it a sprocket chain (similar to the chain 54') which passes over a sprocket wheel upon the 70 arm 7 of the gate 5.

The alarm bell mechanism is preferably mounted on the support 16 and is shown in Figs. 4 and 5. It comprises a train of gears 59 mounted in a supporting frame 60 and actuated by a spring-pressed pawl 61 pivoted upon the arm 6 of the gate 2 as shown. The train of gears actuates a pivoted bell hammer 62 which strikes a bell 63 upon the support 16. When the arm 6 is raised the pawl 61 slips over one of the gears 59 but when said arm is moved downwardly the pawl actuates the gears and the bell is thereby sounded.

In operation, assuming the gates to be open, and a train to be moving over the upper track in Fig. 1 in the direction of the arrow, the trip 42 will be first actuated to draw upon the cable 44 and lift the weighted lever 24. As the latter is elevated its pawl 26 engages the ratchet 29 of disk 19 so that when the lever is permitted to drop by gravity it rotates the disk 19, and, owing to the above described connections between said disk and the arms of all four gates, said arms will be simultaneously lowered to the position shown 90 in full lines in the drawings. After the train passes the crossing it actuates the trip 34 which causes the lever 23 to be elevated. When lever 23 descends it turns disk 19 in the opposite direction to lower the gate arms. 100 When the levers 23, 24 reach their lowered positions their pawls 26 are automatically disengaged from the ratchets 29 by the engagement of their cam ends 31 with the trip 32. When the arm 6 of the gate 2 descends 105 the bell 63 will be sounded as above described. When the train passes in the opposite direction over the other track the trip levers 43, 33 will be successively operated and the operation of the other parts of the 110 invention will be the same. It will be understood that the trip levers are arranged at suitable distances from the crossing.

From the foregoing it will be seen that my invention provides a railway crossing gate 115 which is simple, strong, durable inexpensive, reliable, efficient and entirely automatic in its operation.

Various changes in the form, proportion and minor details of construction may be resorted to without departing from the spirit or sacrificing any of the advantages of the 120 invention.

Having thus described my invention what I claim is:

1. In a railway gate, the combination of 125 a pivoted gate a sprocket wheel carried by the gate, an oscillatory element, a sprocket chain passed around the wheel and connected to said element, oppositely arranged 130

ratchets upon said element, weighted levers, spring-actuated pawls carried by the levers for engagement with said ratchets, means for disengaging the pawls from the ratchets, 5 and means for lifting said levers.

2. In a railway gate, the combination of a gate, an oscillatory element for actuating the same, a ratchet upon said element, a weighted lever, a pawl carried by the lever 10 for engagement with the ratchet when the lever is elevated, and means for disengaging the pawl from the ratchet when the lever is lowered.

3. In a railway gate, the combination of a 15 gate, an oscillatory element for actuating the same, oppositely arranged ratchets upon said element, weighted levers, spring actuated pawls pivoted upon the levers for engagement with the ratchets when the levers 20 are lifted, and means arranged in the path of the pawls for disengaging them from the ratchets when the levers are lowered.

4. In a railway gate, the combination of a 25 plurality of gate arms operatively connected for simultaneous swinging movement, an oscillatory element provided with oppositely arranged ratchets, weighted levers fulcrumed concentric with said element, spring actuated pawls pivoted upon the 30 levers for engagement with the ratchets, means arranged in the path of the pawls for disengaging them from the ratchets, trip devices adapted to be actuated by passing cars, and operative connections between said 35 trip devices and said levers, substantially as described.

5. In a railway gate, the combination of a 40 gate, an oscillatory element for actuating the same, a pair of oppositely disposed levers having their inner ends pivoted and their free ends weighted, pawls carried by said levers for engaging said element and actuating it in opposite directions when said levers

move downwardly, and means for elevating 45 said levers.

6. In a railway gate, the combination of a gate, an oscillatory element for actuating the same, a pair of oppositely disposed levers having their inner ends pivoted and their free ends weighted, pawls carried by said 50 levers for engaging said element and actuating it in opposite directions when said levers moved downwardly, means for disengaging said pawls from said element, trip devices adapted to be actuated by a passing car, and 55 operative connections between said trip devices and said levers.

7. In a railway gate, the combination of a 60 gate, an oscillatory element for actuating the same, a pair of oppositely disposed levers, pawls carried by said levers for engaging and operating said element, means for disengaging said pawls from said element and means for actuating said levers.

8. In a railway gate, the combination of a 65 gate, an oscillatory element for actuating the same, a ratchet upon said element, a lever pivoted concentric with said element and having its free end weighted, a pawl pivoted at one of its ends to said lever and having its 70 free end formed with a curved or cam-shaped portion, the intermediate portion of said pawl being formed with a tooth to engage said ratchet, a spring upon the lever for actuating said pawl, a trip stud adapted to 75 be engaged by the curved end of the pawl to disengage the tooth of the latter from the ratchet, and means for elevating said lever.

In testimony whereof I affix my signature 80 in presence of two witnesses.

JOHN PERNAT.
